JOHN VAUDREUIL, OF MILWAUKEE, WISCONSIN, ASSIGNOR TO SANITARY DISH-WASHING MACHINE COMPANY, OF MILWAUKEE, WISCONSIN, A CORPORATION OF WISCONSIN.

SOAPING DEVICE.

1,418,497.

Specification of Letters Patent.

Entered June 6, 1922.

Application filed November 6, 1920. Serial No. 422,351.

To all whom it may concern:

Be it known that I, JOHN VAUDREUIL, a citizen of the United States, and resident of Milwaukee, in the county of Milwaukee and State of Wisconsin, have invented new and useful Improvements in Soaping Devices, of which the following is a description, reference being had to the accompanying drawings, which are a part of this specification.

10 The invention relates to soaping devices for dishwashing machines.

The object of the invention is to provide a soaping device acting automatically to supply the dishwashing machine with a 15 charge of soapy water, the soap being discharged from the device by turning the supply water on and off.

The invention further consists in the several features hereinafter described and more 20 particularly defined by claims at the conclusion hereof.

In the drawings: Fig. 1 is a view of the device embodying the invention applied to a dishwashing machine; Fig. 2 is a vertical 25 sectional view through the device.

In the drawings the numeral 3 designates a dishwashing machine to which washing water is conveyed by a pipe 4. A pipe 5 connects pipe 4 with a source of cold water 30 supply 6 and a pipe 7 connects pipe 4 with a source of hot water supply 8. Valves 9 and 10 control the passage of water through the pipes 5 and 7 respectively. The dishwashing machine is here shown mounted on 35 a sink 11 and the supply pipes 6 and 8 have faucets 12 and 13 connected thereto.

A coupling member 14 has threaded engagement with the upper end of the pipe 4 at one end and threaded engagement with 40 the base portion 15 of a soap receptacle 16 at its upper end. The coupling member 14 is provided with an inwardly extending flange 17 forming a seat 18 for a ball valve 19. This valve may be of metal, glass, vitrified 45 clay or wood.

The base portion 15 has a centrally disposed passage 20 communicating with the interior of the coupling and a valve seat 21 at the lower end of this passage. The upper 50 end of this passage is threaded to receive a tube 23.

The tube 23 is threaded at its upper end 24 to receive a nut 25 which clamps a glass shell 26 between the base 15 and a cap 27

engaged by said nut, suitable washers 28 55 being interposed between the edges of the glass and cap 27 and base 15.

The tube 23 is provided with a plurality of openings 29 near its lower end, openings 30 intermediate its ends and openings 31 60 near its upper end. The tube acts as a distributor for the water entering the soap receptacle, preferably from the hot water supply.

When water is admitted to the pipe 4 it 65 lifts the valve 19 and some of it enters the soap receptacle where it comes in contact with the soap therein, which may be soap chips or semi-liquid or liquid soap. As the valve 19 lifts, due to the water pressure, it is 70 moved into engagement with the seat 21, thereby shutting off the passage of water to the soap receptacle. During the time of movement of the valve 19 from the seat 18 to the seat 21 some water has entered the 75 receptacle to dissolve or mix with the soap or soap solution therein. When the water is shut off from the machine the valve 19 drops down to the seat 18 and the soap solution then fills the space or chamber 32 above 80 the valve. When the water supply is again turned on and off some of this soap solution above the valve will be carried down below it and into the pipe 4 and thence to the machine, the ball itself assisting in ejecting the 85 soap solution into the pipe 4. Thus, a turning on and off of the water supply serves to eject a charge of soap solution into the pipe 4 from whence it passes to the machine along with the water in said pipe to furnish 90 soapy water for washing the dishes. After the charge of soap has been carried through the pipe 4 continued flow of the clear water holds the valve 19 to its upper seat 21 and the clear water enters the machine to rinse 95 the dishes.

What I claim as my invention is:

1. The combination, with the pipe for conducting water to a dishwashing machine, of a soap receptacle communicating with 100 said pipe, and a valve controlling the passage of water to said receptacle, said valve having two closing positions and being movable between said positions to permit and assist in the passage of soap solution into said pipe when the water supply is turned on and off.

2. The combination, with the pipe for

- conducting water to a dishwashing machine, of a soap receptacle communicating with said pipe including a distributor tube, and a valve controlling the passage of water to 5 said receptacle, said valve having two closing positions and being movable between said positions to permit and assist in the passage of soap solution into said pipe when the water supply is turned on and off.
- 10 3. The combination, with the pipe for conducting water to a dishwashing machine, of a soap receptacle communicating with said pipe, a ball valve controlling the passage of water to said receptacle, said 15 valve having two closing positions and being movable between said positions to permit and assist in the passage of soapy water into said pipe when the water supply is turned on and off.
- 20 4. The combination, with the pipe for conducting water to a dishwashing machine, of a soap receptacle and a passage between said receptacle and pipe, said passage including a chamber having valve seats in its 25 top and bottom, a valve in said chamber movable between said seats on an increase or decrease in pressure of the water in said pipe, said valve permitting and assisting
- in the passage of soap from said receptacle into said pipe. 30
5. The combination, with the pipe for conducting water to a dishwashing machine, of a soap receptacle and a passage between said receptacle and pipe, said passage including a chamber having valve seats in its 35 top and bottom, a ball valve in said chamber movable between said seats on an increase or decrease in the pressure of the water in said pipe, and a distributor tube connected to said passage and projecting into said 40 soap receptacle, said tube having lengthwise spaced openings.
6. The combination, with a supply pipe, of a soap receptacle and a passage between said receptacle and pipe, said passage including a chamber having a valve seat at its upper end and a lower valve engaging portion, a valve in said chamber movable between said seat and the lower end of the chamber on an increase or decrease in pressure of the water in said pipe, said valve 45 permitting and assisting in the passage of soap from said receptacle into said pipe. 50

In testimony whereof, I affix my signature.

JOHN VAUDREUIL.
